UNITED STATES PATENT OFFICE.

RONALD M. DE ROSA, OF SAN FRANCISCO, CALIFORNIA.

HAND LIFT FOR HARROWS.

Application filed June 28, 1926. Serial No. 119,004.

This invention relates to improvements in devices for raising and lowering the ground engaging members of harrows; my principal objects being to provide a hand lift mechanism, preferably in the form of an attachment, to be applied to the ordinary operating lever of the harrows, by means of which said lever may be more easily operated to raise and lower the ground engaging members than is at present the case; and so constructed that it is not necessary to stop the progress of the harrow in order to move said members, and the same will be automatically held in either raised or lowered positions without the need of any pawl and ratchet or similar holding mechanism. My hand lever device is also so constructed as to be very easy to operate, and there is nothing to get out of order or fail to function.

While my device functions with a single lever harrow, it is especially valuable in connection with two or three section harrows, having a corresponding number of levers, since with my device applied thereto all the levers are operated simultaneously. This is obviously a great improvement over the present construction which necessitates each lever being operated individually, and with the employment of considerable physical effort.

I have here shown and described the operating device as being applied to a spring-tooth harrow, but it is obvious that said device can be utilized in connection with the control lever of a harrow having any form of ground engaging members.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of an ordinary spring tooth harrow showing my hand lever device applied thereto and with the teeth in their raised positions.

Fig. 2 is a similar view showing the teeth lowered.

Referring now more particularly to the characters of reference on the drawings, the numeral 1 denotes the frame of the harrow having a plurality of longitudinally spaced transverse shafts or similar turnable elements on which are fixed the spring teeth 3. Projecting upwardly from the members 2 are arms 4 connected by a common link 5. The rearmost arm 4 has an upwardly extending lever 6 associated therewith, by means of which said arms may be swung one way or the other, and the teeth consequently raised from or lowered into the ground.

The ratchet and quadrant mechanism usually associated with the lever to enable the same to be maintained set, I do not need or use and hence have omitted showing the same on the drawing. If the harrow is a two or three section implement, there are a like number of levers and arm and link connections, all said levers being disposed in parallel transverse alinement.

My improved hand lever device to be applied to such standard parts comprises a longitudinal arm 7 pivoted on a bracket or lug 8 which is mounted at the front of the frame 1. The opposite end of said arm is pivoted onto another and longer arm 9 intermediate the ends of the latter. The lower end of the arm 9 is pivoted onto a bracket 10 which is clamped onto the lever 6 intermediate its ends and in front of the same by suitable means such as U bolts 11. If two or more levers are provided on the implement a transverse beam 12 is provided in connection with the bracket 10 so as to extend across all the levers in front of the same and to be clamped thereto. The other end of the arm 9 has an angular extension 13 projecting at an acute angle to the longitudinal plane of said arm in an upward and forward direction when said arm is horizontally disposed. A pull rope 14 or the like is applied to the outer end of this extension.

A tension spring 15 extends from the pivotal connection of the arm 9 with the bracket 10 to a connection with the arm 7 intermediate its ends. The arm 9 is provided with a plurality of longitudinally spaced holes

16, so that the connecting bolt or pin 17 of the arm 7 may be applied to any one of said holes and thus alter the operative length of the arms when the latter are in a certain position, and consequently the depth to which the teeth may project may be altered, as will be hereinafter seen.

The arms 7 and 9 are so arranged relative to each other that when the teeth are 10 out of the ground, and the lever 6 and arms 4 are disposed at a forward angle, the arm 9 will also be disposed at a forward angle, the extension 13 at a rearward angle, and the arm 9 at an upward and rearward 15 angle. The spring 15 is then below the pivotal connection of the bolt 17 with the arm 9 and is in tension. The spring therefore constantly acts to pull the lever 6 further forward but cannot do so since it also 20 tends to pull the arm 7 downward and rearwardly. Consequently the spring pressure is equalized and the lever and arm structures are maintained in the positions to which they have been moved by a rearward 25 pull on the extension 13 by means of the rope 14.

When it is desired to lower the teeth the rope 14 is pulled from ahead. This causes the arm 9 to be swung about the pin 17 as 30 an axis, since the rod 7 is rigid. The upper portion of the arm 9 therefore moves forward and downward and the lower portion is moved rearwardly, turning on its connection with the bracket 10 and forcing the lever 6 rearwardly about its axis. This causes a rearward rotation of the shaft 2 and consequently a rearward rotation of the teeth 3 to take place. The pull on the rope 14 is maintained until the arms 7 and 9 40 move past a longitudinally alined position, or past dead-center position with respect to the location of the pin 17 relative to the opposite pivoted ends of the arms 7 and 9 with the frame and lever respectively. The spring 15 then being still in tension acts to 45 increase this past dead-center position, as will be evident, preventing any tendency of the teeth to leave the ground.

Further downward movement of the arms 50 is limited by the forward end of the arm 7 engaging the forward shaft 2 or the frame 1.

The rearward angular setting of the lever 6 and associated parts and consequently the 55 depth to which the teeth will enter the ground is controlled by altering the point of connection of the bolt 17 with respect to the length of the arm 9, since, as will be evident, when the arms are in the last 60 named position, the operative length of said arms between their opposed pivots will be shortened or lengthened by changing the bolt 17 from one to another of the longitudinally spaced holes 16.

While I have specifically described and

shown this device as being an attachment to be applied to harrows as now constructed, it will be obvious that my device may if desired be actually built into the harrow during the manufacture of the same.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended 75 80 85 90 95 100 105 110 115 120 125 130 claims.

Having thus described my invention what I claim as new and useful and desire to secure by Letters Patent is:

1. A hand-lift structure for a harrow, 85 said harrow including a frame, ground engaging members turnably mounted thereon, a longitudinally movable lever pivoted on the frame and means operatively connecting the lever and members to cause the latter 90 to be turned with the movement of the lever; comprising an arm pivotally connected to the lever and extending ahead of the same, another arm pivoted at one end onto said first named arm and at its other end onto 95 the frame at the forward end of the same, an operating member attached to the outer end of the first named arm, said arms when the teeth are out of the ground projecting upwardly at an angle to each other and when the teeth are in the ground moving down past dead center with respect to the pivotal connections at the ends of the arms, and spring means applied to the arms to maintain the same in either of the above 100 105 named positions.

2. A hand-lift structure for a harrow, 110 said harrow including a frame, ground engaging members turnably mounted thereon, a longitudinally movable lever pivoted on the frame and means operatively connecting the lever and members to cause the latter to be turned with the movement of the lever; comprising an arm pivotally connected to the lever and extending ahead of the same, another arm pivoted at one end onto said 115 first named arm and at its other end onto the frame at the forward end of the same, an operating member attached to the outer end of the first named arm, said arms when the teeth are out of the ground projecting 120 upwardly at an angle to each other and when the teeth are in the ground moving down past dead center with respect to the pivotal connections at the ends of the arms, 125 and a compression spring connected to the first named arm below the connection of the second named arm therewith and to the second named arm intermediate its ends.

3. A hand-lift structure for a harrow,

said harrow including a frame, ground engaging members turnably mounted thereon, a longitudinally movable lever pivoted on the frame and means operatively connecting the lever and members to cause the latter to be turned with the movement of the lever; comprising an arm pivotally connected to the lever and extending ahead of the same, another arm pivoted at one end onto said

first named arm and at its other end onto the frame at the forward end of the same, and a further arm rigidly connected to the first named arm adjacent its outer end and projecting ahead of said arm at an acute upward angle therewith. 15

In testimony whereof I affix my signature.

RONALD M. DE ROSA.
